W. N. Raines,
Railroad Switch,
No. 8,557, Patented Dec. 2, 1851.

FIG. 1.

FIG. 2.

UNITED STATES PATENT OFFICE.

WM. N. RAINES, OF THOMSON, GEORGIA.

RAILROAD-SWITCH.

Specification of Letters Patent No. 8,557, dated December 2, 1851.

To all whom it may concern:

Be it known that I, WILLIAM N. RAINES, of Thomson, in the county of Columbia and State of Georgia, have invented a new and 5 useful Improvement in the Construction of Railroad-Switches; and I do hereby declare the following to be a full and clear description thereof, reference being had to the annexed drawings, making part of this specification.

Figure 1, is a top or vertical view of the switch as adjusted to the turnout rails of the track. Fig. 2, is ditto, the switch being adjusted to the main rail of the track.

15 The same letters on the figures indicate the same parts.

I am aware that switches have been used composed of short rails corresponding with the turn out rails; as well as additional 20 branches furnished with inclined planes to receive the flanges of the car wheels between said short rails and branches to allow the train of cars to pass over the main rails, when the switch is adjusted to the turn-out rails.

25 And also providing the switches on the outsides thereof and next to the inclined planes with guards to keep the flanges of the wheels in the grooves of the inclined plane. But I am not aware of the construction and 30 use of a stationary casting so constructed as to serve the purpose of the ordinary frog and switch in connection with the turn-out side of the main rail—said stationary casting having formed thereon a section connect-

35 ing permanently the main rail and turnout—and also furnished on the inside thereof with a guard, the object of which being especially to guide the flanges of the wheels in a straight line in passing over said stationary casting when the switch is adjusted to the turn-out as in Fig. 1, and the opposite wheels are rising the inclined plane between the turn-out and main rail. Nor am I aware that a switch furnished on the inside thereof with a guard to guide the flanges of the wheels over the switch to the main rail has been employed and combined 40 with the movable casting in the manner represented,—whereby the single switch is 45 made to connect with the turn-out rail and, at the same time the cars being permitted to pass thereover from the main rail in either direction as seen in Fig. 2, and much time saved in not requiring attendance in

50 running trains out of the side lines into the 55 main track by not being required to adjust the switch to the turnout rails.

a a are the main rails of the track.

b b, are the turn out rails.

c is the permanent casting connecting with 60 the main rail *a*, and turn-out *b* by the short rail *d*, and containing the inside guard *e*, and having placed thereon between the guard *e*, and connecting rail *d*, a frog *f* forming an angular termination of the 65 main-rail *a* on the stationary casting, whereby the latter is made to constitute an auxiliary switch and frog to the turn-out rails.

g is the switch also composed of a single casting and pivoted at *h* and provided with 70 a groove, the bottom whereof forms an inclined plane *i* of sufficient depth to receive the flanges of the wheels when the cars are running in the direction of the arrow *y* and the switch *g* has been accidentally left set 75 for the turn out or side line *b* as shown in Fig. 1, whereby the flange of each wheel will pass from the inclined plane *i* over the broad surface *k* till it reaches the main rail *a* at *h*, when the flanges will drop on 80 the inside of the main rail. During the passage of the flanges over the surface *k*, the guard *e* of the permanent casting *c* serves to guide the wheels over said permanent casting in a straight line and thus prevent the train 85 passing laterally off the surface *k* of the switch *g*, said guard *e* fitting against the inside of the flanges of the wheels, while the train of cars is passing.

On the casting *g*, and adjacent to the 90 groove of the inclined plane *i*, there is formed a solid surface *l*, the level of the upper surface of which being coincident with that of the rails *a*, *b*, the use of which in connection with the surface *k* is to form 95 a continuation of the main rails *a*, when the switch is adjusted thereto as represented in Fig. 2, and also a connection of the turnout and main rail as shown in Fig. 1, over which the tread of the wheels passes in 100 either direction on and to the turnout rail *b* in the direction of the arrow *y*.

Between the solid surface *l* and guard *m* there is cast a wedge shaped projection or frog *n*, for the purpose of forming a connection of the turn-out rail *b* with the switch *g* when the train of cars is passing from the turn-out or side line *b* on to the main rail *a* as shown by the arrow *y*. Fig. 2.

m is the guard cast on the inside of the 110

switch g . The especial use of this guard m is to guide the wheels of the train over the switch g in a straight line, when passing in the direction of the arrow y^3 Fig. 2, where-
5 by the train is prevented from moving laterally to the left or passing on to the turn-
out rails b , and also whereby the tread of the
wheels passing over the permanent casting is
prevented from striking the point of the
10 frog or wedge shaped projection f , and for
this purpose a portion of the inside of the
guard m must be on a line coincident with
the side of the frog or wedge shaped pro-
jection n , nearest the outer rail as shown by
15 the dotted line $s s$, and the frog or wedge
shaped projection f of the permanent cast-
ing must be longer than the projection or
frog n of the casting g , whereby the flanges
20 of the wheels passing over the latter are
made to pass between the frog or projection
 f and the guard e , before the flanges of the
wheels passing over the switch g leave the
guard m or pass the dotted lines $x x$, and
thus perfect safety is insured to the train in
25 passing in either direction over the switch;
or from the turn-out rails b in the direc-
tion of the arrow y^2 , Fig. 2.

The switch casting g is connected and op-
erated by the usual switch bar o and ball
30 lever p .

Having thus described my invention and

improvement and pointed out the difference
between the same and other railroad
switches, what I claim therein as new and
desire to secure by Letters Patent, is—

35

1. The combination of the stationary sin-
gle casting c with the single casting or
switch g , each having a guard on the inside
thereof, whereby the said permanent single
stationary casting c is made to subserve the 40
purpose of the ordinary frog and auxiliary
switch in connection with the turn-out side
of the main track as described.

2. I also claim providing the movable
casting g on the inside thereof with a guard 45
 m for the purpose of guiding the train of
cars over the switch in a straight line when
running in the direction of the arrow y^3 ,
and thus prevent the cars from passing on to
the turn-out rails, when the switch is in the 50
position shown in Fig. 2, the projection or
frog f , being of sufficient length in connec-
tion with guard m to guide the train on to
the main rail a , as described.

In testimony whereof I have hereunto 55
signed my name before two subscribing wit-
nesses.

WM. N. RAINES.
